SPARK PLUG

Roy T. Hurley, Dobbs Ferry, N. Y., assignor to
 Hurley-Townsend Corporation, New York,
 N. Y., a corporation of Delaware

Application March 13, 1930, Serial No. 435,461

10 Claims. (Cl. 123—169)

This invention relates to spark plugs and has for an important object the provision of a spark plug which will be well sealed at all times against the escape of gases through it and which will, as a consequence, be well adapted to avoid overheating even under the exacting conditions imposed in heavy duty engines, such as those employed in airplanes and in racing automobiles.

Other objects and advantages will hereinafter appear.

In the drawing forming part of this specification,

Figure 1 is a vertical sectional view taken centrally through a spark plug embodying feature 15 of the invention.

Figure 2 is a vertical, sectional, detail view through an expandible sleeve employed in the spark plug of Figure 1;

Figure 3 is a plan view of the sleeve of Figure 2;

Figure 4 is a sectional view taken on the line 4—4 of Figure 2, looking in the direction of the arrows; and

Figure 5 is a vertical, sectional view through a modified form of expandible sleeve which may be employed.

The illustrative spark plug comprises an externally threaded shell 1 adapted to be threaded into a motor. The shell 1 carries a spark electrode 2 which forms one terminal of the spark gap. An insulator and central electrode assembly 3 comprises an externally threaded nut 4 which is screwed tightly into the shell 1 to contact with the shell in firmly clamping an interposed gasket 5 to form a tight seal. The nut 4 serves as a retaining and supporting member for the central assembly 3.

The central assembly 3 also comprises an expanded sleeve 6, (see Figures 2 and 3) of malleable metal having high heat conductivity, such as copper. This sleeve is provided with a flange 7 at the lower end thereof. It is upon this sleeve that the central assembly is built up. The sleeve 6 may be initially a cylindrical tube provided with the flange 7, but before the steps of incorporating it in a spark plug are begun, longitudinally extending grooves 8 are formed in the outer face of the tube. The grooves 8 terminate a short distance above the lower end of the sleeve. Since the formation of the grooves displaces some of the metal inward, the outside diameter of that length of the sleeve in which the grooves have been formed is reduced by the formation of the grooves and is less than that of the ungrooved lower end portion.

A sheet of compressible, heat-resisting, insulating material, such as mica, is next snugly wrapped around the sleeve 6 in the form of a multiple-ply tube 9. Upon this tube 9 the lower end 10 of the insulator is built up of washers of suitable insulating material, such as mica. The nut 4 is then impaled upon the tube and the upper end 11 of the insulator is built up by placing upon the tube further washers of mica or other suitable material. As thus assembled, the 10 nut 4 does not bind upon the tube 9 but fits it rather snugly.

The central electrode is next inserted in the sleeve 6 from the lower end thereof. The central electrode comprises a shank 12 and a nose 13, the nose being larger than the shank, but of such small mass that the heat absorbed by it may be rapidly and efficiently conducted away, principally by the shank 12 and the sleeve 6. The central electrode is desirably made of steel 20 or other suitable material that will resist oxidation by the combustion in the engine. The nose 13 carries a sparking tip 14 of suitable material, such as nickel-manganese wire.

Prior to the insertion of the central electrode, 25 the sleeve, insulator and nut assembly is longitudinally compressed, and this pressure is maintained throughout the insertion of the electrode.

The shank 12 of the central electrode is of a diameter to snugly fit within the ungrooved 30 lower end of the sleeve 6. It may be started in the sleeve readily therefore, but when it reaches the internal ribs formed by grooving of the exterior of the sleeve, it must be driven. This driving of the electrode through the sleeve eliminates the grooves and expands the grooved portion of the sleeve to the diameter of the ungrooved portion. Such expansion of the sleeve 6 simultaneously applies circumferential tension 40 and radial pressure to the tube wall 9 so that the tube wall is pressed with considerable force between the sleeve and the nut 4. The shank 12 and the sleeve 6 have at least as high coefficients of heat expansion as the nut 4, so that this pressure is not relieved when the spark plug 45 becomes heated in use.

After the insertion of the central electrode, the conductive terminal 15 is placed upon the upper end of the shank 12 and the upper end of the shank is upset, as shown at 16, to hold the parts in assembled relation and under pressure.

The described construction is efficient under all operating conditions and is especially efficient under heavy duty conditions of operation because 55

the central electrode does not tend to overheat and cause pre-ignition. As has been stated, the shank 12 of the central electrode is relied on largely for conducting away the heat absorbed by the electrode nose 13. In order that the shank may perform this function efficiently, it is important that the shank be protected against the circulation of hot gases around it, since the absorption of heat by the shank from any source other than the electrode nose will necessarily reduce the temperature gradient of the shank. It is of especial importance that the circulation of gases between the shank and the nut be avoided because the mass of metal forming the nut 4 serves as an effective means of withdrawing heat from the shank at the point where the insulation is of minimum thickness. The described construction is effective to maintain the shank and sleeve in as intimate heat-transferring relationship with the nut 4 as is consistent with maintaining good electrical insulation between the shank and the nut.

In Figure 5 a modified sleeve 6A is illustrated. This sleeve is not grooved like the sleeve 6 but includes a portion 17 of reduced diameter. The sleeve is assembled with the insulator and nut elements in the same manner as the sleeve 6 already described. It would not be practicable to drive the electrode rod directly into this sleeve for the purpose of expanding it. Such expansion may be accomplished, however, by introducing a steel ball 18 in advance of the electrode 12 and driving it through the reduced portion of the sleeve in advance of the electrode 12. The construction and operation of the finished assembly is the same as that illustrated in Figure 1.

While I have illustrated and described in detail certain preferred forms of my invention, it is to be understood that changes may be made therein and the invention embodied in other structures. I do not, therefore, desire to limit myself to the specific constructions illustrated, but intend to cover my invention broadly in whatever form its principle may be utilized.

45 I claim:

1. In a spark plug the combination with a shell, of a nut threaded in the shell, a central electrode, a tube of insulating material interposed between the central electrode and the nut, 50 and a radially expanded member snugly fitting the electrode and radially compressing the insulating tube against the nut.

2. In a spark plug, a central electrode, a tube of insulating material surrounding the same, a metallic retaining member surrounding the tube of insulating material, and an expansible sleeve interposed between the central electrode and the insulating tube and expanding the said sleeve into firmly sealed engagement with the metallic 55 retaining member.

3. In a spark plug, the combination with a central electrode of a tube of insulating material surrounding the same, a metallic retaining member surrounding the tube of insulating material,

and means including an expansible metal sleeve member cooperating with the electrode simultaneously to stretch the insulating tube circumferentially and to compress it radially against the metallic retaining member to form an effective seal.

4. In a spark plug, the combination with a central electrode and a metallic retaining member surrounding the same, of an insulating tube interposed between the electrode and the retaining member and an expansible sleeve member positioned within said tube and maintained under circumferential tension and under radial compression for forming a seal.

5. In a spark plug, the combination with a central electrode, of a retaining member surrounding the electrode, and a sealing tube interposed between the electrode and the retaining member and an expanding sleeve interposed between the sealing sleeve and the electrode and maintaining the tube under circumferential tension and under radial compression for forming a seal.

6. In a spark plug, in combination, a central electrode having a cylindrical shank, an expanding sleeve surrounding the shank, an insulating tube on the sleeve, and a heat conductive retaining member surrounding the tube, the tube being expanded by the sleeve and pressed by it into sealing engagement with the retaining member.

7. In a spark plug, in combination, a central electrode having a cylindrical shank and a nose larger than the shank, an expanding sleeve surrounding the shank, an insulating tube on the sleeve, and a heat conductive retaining member surrounding the tube, having no greater coefficient of expansion than the electrode, the tube being expanded by the sleeve and pressed by it into sealing engagement with the retaining member.

8. An expanding sleeve for use in spark plugs having a circumferential flange portion at one of its ends and a tubular portion, the end of the tubular portion adjacent the flange being ungrooved and the remainder of the length of the tubular portion being externally, longitudinally grooved.

9. An expanding sleeve for use in spark plugs having a circumferential flange portion at one of its ends and a tubular portion, the end of the tubular portion adjacent the flange being cylindrical and of a diameter to receive the spark plug electrode snugly, and the remainder of the length of the tubular portion being of less diameter, so that it will be expanded by the driving of the electrode into it.

10. In a spark plug, the combination of a body piece having a central opening, a metallic quill passing through said opening, an insulating sleeve surrounding the quill, and a central metallic spindle driven into the quill so as to expand the same to grip the insulating sleeve against the surrounding surface of the opening in the body piece.

ROY T. HURLEY.
